(57) **CLAIM**

The ornamental design for a vacuum cleaner, as shown and described.

DESCRIPTION

FIG. 1 is a top view of the canister portion showing my new design;

FIG. 2 is a bottom view of FIG. 1;

FIG. 3 is a left side view of FIG. 1;

FIG. 4 is a right side view of FIG. 1;

FIG. 5 is a front view of FIG. 1;

FIG. 6 is a rear view of FIG. 1;

FIG. 7 is a perspective view of FIG. 1;

FIG. 8 is a perspective view showing the claim in fully assembled condition, the vacuum head and attachments shown in broken lines form no part of the claimed design;

FIG. 9 is a front perspective view of the handle, the portion of the hose is shown broken away for ease of illustration;

FIG. 10 is a side view of FIG. 8; and,

FIG. 11 is a rear perspective view of FIG. 8.

The canister and handle are shown separate in FIGS. 1-7 and 9-11 for clarity of illustration.
